UNITED STATES PATENT OFFICE.

HAROLD B. FUNCK, OF SEATTLE, WASHINGTON.

AEROPLANE PROPELLER.

Application filed April 17, 1926. Serial No. 102,721.

This invention relates to improvements in aeroplanes and more particularly to the construction of horizontally revolving propellers for aeroplanes of the helicopter type; 5 it being the principal object of the invention to provide propellers capable of producing a much greater lifting power than has heretofore been possible, and wherein provision is made for manual adjustment of the propeller planes in order to increase or decrease the lifting power and to thus control the ascent or descent of the plane.

More specifically stated, the object of the invention resides in the provision of a horizontally revolving propeller comprising a plurality of wing sections extending radially from a vertical supporting and driving shaft, and wherein each wing section embodies a plurality of planes arranged in 10 independent groups and in closely spaced, parallel relation; each group of planes being pivotally supported at its ends and connected with means whereby the incline or tilt may be adjusted as is desired or necessary in order to produce a greater or lesser lifting effect.

Other objects of the invention reside in the various details of construction of the plane sections and in the means for effecting an adjustment, as will be fully described 20 in the following specification.

In accomplishing these objects of the invention, I have provided the improved details of construction, the preferred forms of 25 which are illustrated in the accompanying drawings, wherein—

Figure 1 is a top, or plan, of an aeroplane equipped with a horizontally revolving propeller constructed and mounted in accordance with the details of the present invention.

Figure 2 is an enlarged, vertical section of the propeller taken on the line 2—2 in 30 Figure 1, showing the manner of mounting the propeller planes and means whereby their incline may be regulated.

Figure 3 is an enlarged, cross section through one of the propeller wings taken on the line 3—3 in Figure 2, illustrating the 35 disposition of the several groups of planes within the wing.

Figure 4 is a horizontal section taken on the line 4—4 in Figure 2, illustrating the means for adjusting the planes.

Figure 5 is a cross section on line 5—5 in 55 Figure 2, showing the means interconnecting the groups of planes within the wing.

Referring more in detail to the drawings—

1 designates what may be an aeroplane of 60 the common type now generally in use, with the exception of the usually provided wings or planes, and 2 designates, in its entirety, a propeller of the type embodied by the present invention and which is mounted on the 65 aeroplane to revolve in a horizontal plane; the propeller being supported and driven by means of a vertical shaft 3 which is fixed revolvably within bearings 4 and 5 secured to the body of the aeroplane. The shaft is 70 adapted to be revolvably driven by any suitable means, such as by an engine carried within the plane, and which would be equipped with a driving shaft as herein designated at 6 having geared connection, 75 as at 7 in Figure 2, with the lower end portion of the propeller shaft.

The propeller herein shown is intended primarily for lifting the plane vertically, and while I have not illustrated the aeroplane as equipped with the usual wings for 80 flight, such may be provided if desired or thought necessary. The plane also would be equipped with the usual vertically revolving propeller 8 for driving the plane 85 forwardly.

The propeller 2, in plan, is of cross form as shown in Figure 1, embodying four wings that extend radially from the central supporting and driving shaft 3. Each wing of 90 the propeller comprises a frame made up of upper and lower horizontal plates 9 and 10 which are mounted in vertically spaced relation on the upper end of the driving shaft and are bowed symmetrically toward 95 each other toward their outer ends and are rigidly joined at their ends by a vertical end plate 11. Located between the upper and lower frame plates of each wing, is a plurality of groups of planes 12; each group 100 of planes as herein illustrated comprising five planes that are arranged in parallel relation and which, at their outer ends, are securely attached to vertical end plates 13 and, at their inner ends, to vertical plates 14. 105

Each group of planes is pivotally mounted by means of trunnions, or pivot bolts, 15 that are fixed to the outer end plates and

extended pivotally through the frame end plate 11, and at their inner ends, are supported by trunnions 16 extended through supporting bearings 17 carried by the vertical bars 19 of frame structures that are fitted within and secured to the propeller frame. In the present construction, I have shown, as in Figure 3, each wing to contain six separate groups of planes and these are arranged in an upper and lower row of three each. Each group of planes is adapted to be tilted upwardly or downwardly for the purpose of increasing or decreasing the lifting capacity of the propeller, and all of the groups of planes are connected so that they may be tilted equally and all actuated simultaneously from a common control.

The means provided for tilting the planes comprises a sleeve 20 that is vertically slideable on the driving shaft 3 and is keyed thereto so that it revolves with the shaft. The sleeve is adjustable vertically by means of a lever 21 that is pivotally supported at a point between its ends by a pivot bolt 22 from a bracket 23 that is fixed to the body of the plane, and at one end has a pivotal connection at 24 with a ring 25 that is revolvably fixed to the lower end of the sleeve. At its outer end, the lever has a slot 26 through which a bolt 27 that is fixed to the frame of the plane extends. A hand operated nut 28 is threaded onto the bolt and extended through the slot in the lever and, by its adjustment, the lever may be actuated to raise or lower the sleeve.

The supporting trunnions 16, at the inner ends of the two central groups of planes in each wing, extend inwardly and at their inner ends are provided with cranks 30 which are connected, by means of links 31, with ears 32 formed on the upper end of the sleeve 20 so that, by vertical adjustment of the sleeve, the trunnions will be caused to be rotated and, by their rotation, will change the tilt or incline of the planes in each group. The planes of the outer groups in each wing are connected so as to be adjustable from the central groups by means comprising crank arms 35 that are fixed to the inner ends of the supporting trunnions 16 and cross bars 37 which connect these crank arms with cranks 38 that are fixed to the trunnions of the central groups, as is shown best in Figure 5.

A propeller of this type preferably would be constructed of a light, durable material such as aluminum alloy and the planes would be composed of relatively thin sheets of aluminum secured at their ends to the plates 13 and 14. The planes may be kept taut by means of tightening nuts 40 that are threaded onto the supporting trunnions 16 against the supporting bearings.

While I have illustrated each wing to contain six groups of five planes each, it is read-

ily apparent that more or less planes may be used in each group and more or less groups may be provided in each wing.

It is also apparent that various other means than is herein illustrated may be provided for supporting the groups of planes and for effecting their adjustment, and for this reason, it is not desired that the claims be limited only to the means herein illustrated.

It is readily apparent that a propeller so constructed and revolvably driven in a horizontal plane will effect a much greater lifting power than is possible by the use of a single plane in each wing, and that the lifting power may be varied by tilting the planes to different angles. While I do not contend that the lifting power of such a propeller increases in proportion to the number of planes used, it is believed that the lifting power is materially increased by the use of a multiplicity of planes arranged so that each plane will receive the air against its under side.

It is further apparent that the planes 12 need not be pivotally mounted if this is not desired, but could be fixed rigidly within the frame of the propeller at a certain pitch which might be found to be the most desirable.

Having thus described my invention, what I claim as new therein and desire to secure by Letters Patent, is:

1. A propeller of the character described comprising a horizontally revoluble frame structure embodying a plurality of radially directed wings, each wing containing a plurality of horizontally disposed and pivotally mounted groups of planes with the planes of each group permanently fixed in closely spaced, parallel relation one above the other, and means for simultaneously adjusting the pitch of all of the groups of planes.

2. A propeller of the character described comprising a horizontally revoluble frame structure embodying a plurality of radially directed wing sections, each wing comprising upper and lower spaced apart frame plates that are bowed toward each other toward their outer ends and joined by a vertical end plate, a plurality of groups of planes mounted within each wing section; said planes of each group being disposed lengthwise of the wing in closely spaced relation, trunnions pivotally supporting the several groups of planes in the wings, and means operable to simultaneously adjust the pitch of all of the planes.

3. A propeller of the character described comprising a vertical, revolvably driven shaft, a propeller frame fixed to the upper end of the shaft to revolve therewith in a horizontal plane, said propeller frame being of cross form with wing sections extended radially from the shaft; each wing comprising upper

and lower frame plates and connecting plates at their ends, a plurality of groups of planes mounted in each wing section longitudinally thereof; each group comprising a plurality of parallel spaced planes, fixed at their ends to inner and outer end plates, trunnions fixed to said end plates for pivotally mounting

the groups of planes and means for adjusting the planes to different pitch and for retaining them at different positions of adjustment. 10

Signed at Seattle, Washington, this 8th day of April, 1926.

HAROLD B. FUNCK.
